ROTARY TOOL

David Bruzon, Chicago, Ill., assignor to Perfection
Auto Parts Mfg. Co., Chicago, Ill., a corpora-
tion of Illinois

Application November 3, 1938, Serial No. 238,547

3 Claims. (Cl. 144—32)

This invention relates to improvements in screw driver bits and wrench sockets and more particularly to such as are used with power driven means.

5 An object of this invention is the provision of a screw driver bit and wrench socket in which the torque of the operating means is applied to a screw or nut to drive same and is released when the operation is completed.

10 Another object of this invention is the provision of a screw driver bit and wrench socket which completely eliminates the possibility of shearing off of the head from the body of the screw.

15 A further object of this invention is the provision of a screw driver bit and wrench socket which is adapted for securement to any power driven spindle.

20 A still further object of this invention is the provision of a screw driver bit and wrench socket which operates with equal efficiency in either direction of rotation to drive or to remove nuts, bolts and screws.

25 A still further object of this invention is the provision of a screw driver bit and wrench socket which is extremely simple and durable in construction, which has very few parts and which can be manufactured at low cost.

With the foregoing and other objects in view, 30 the invention consists of the novel construction, combination and arrangement of parts, as hereinafter more specifically described and illustrated in the accompanying drawing, wherein is shown a device in accordance with this invention, but 35 it is to be understood that changes, variations and modifications can be resorted to which fall within the scope of the appended claims.

In the drawing wherein like reference characters denote corresponding parts through the several views:

40 Fig. 1 is an elevational view of the screw driver bit.

Fig. 2 is a vertical sectional view taken on line 2—2 of Fig. 1.

45 Fig. 3 is an enlarged plan view of a clutch member.

Fig. 4 is an enlarged elevational view of the clutch members in operative engagement.

In the drawing wherein is shown a preferred 50 embodiment of my invention the numeral 10 designates the screw driver assembly which is adapted to be secured to a driving spindle by means of a chuck 12. The screw driver assembly 10 comprises a housing formed of two cylindrical members, an upper member 14 having an externally

threaded portion 15 and a lower member 16 having an internally threaded portion 18 and apertured as at 20 to receive the driven spindle 17, presently to be described. The member 14 is provided with a spindle extension 21 integrally 5 formed therewith which is adapted to be secured in the jaws of the chuck 12. A hole 22 is provided in the upper member 14 for lubricating purposes.

Rigidly secured as by a pin 24 in the upper 10 housing member 14 is a clutch member 25 having an exposed corrugated surface 26 with alternate ribs and recesses, substantially triangular in cross section, radiating from the center. Rotatably and slidably mounted in the housing member 14 is a longitudinally bored driven spindle 17 which is provided, at one end, with a slot 28 and at the other end with an enlarged portion 30 having a complementary corrugated surface 32 adapted for engagement with the clutch member 25. A coil spring 34 positioned in the housing member 16 and encircling the spindle 17 bears against bushings 36 and 38 and serves to retain the clutch member 25 and 30 in resilient engagement. 25

It is seen that by advancing or receding the housing members 14 and 16 with respect to each other the compression of the spring 34 can be adjusted to increase or decrease the torque to a predetermined point. A set screw 38 serves to 30 retain the housing members 14 and 16 in adjusted relative position.

A screw driver bit 40 is reciprocally mounted in the bore 49 of the driven spindle 17 and is operatively connected thereto by a pin 42 which extends through the bit 40 and which operates in the slot 28 of the driven spindle 17 to cause the bit 40 and spindle 17 to rotate simultaneously. A spring 44 mounted in the core 49 of the driven spindle 17, at one end, bears against the enlarged portion 30 of the spindle 17 and at the other end, against a shoulder 41 formed on the screw driver bit 40 and serves to yieldingly hold the bit 40 in outermost position. 40

An inverted cup shaped member 46 mounted on the bit 40 encloses the lower end of same and serves as a guide or finder for the screw. The bit 40 is provided with a circumferential groove 47 in which is seated a spring ring 48 which acts as 50 a shoulder to secure the member 46 on the bit 40. A helical spring 50 encircling the bit 40 yieldingly maintains the member 46 at the extreme portion of the bit. While a screw driver bit is illustrated, it will be understood that a 55

socket wrench may be substituted therefor to drive nuts and bolts.

In operation, the clutch faces 26 and 32 are always in engaged relation and the tool rotates continuously as a unit. When the tool is brought in contact with the work the spring 50 permits the guide member 46 to yield while alignment between the bit 40 and the slot of the screw is being effected. When the point of the bit 40 registers in the screw slot, slight pressure compresses the spring 50 and causes the bit to recede within the longitudinal bore 49 of the driven spindle 11. It will be seen that the yielding arrangement of the guide 46 and the bit 40 is such that the defacing or marring of the work is completely avoided.

Assuming that a specified torque is required for a particular job and that an adjustment for same has been made on the spring 34, it will be seen that during the driving operation the driven spindle 11 rotates with the driving spindle 21. However, when the torsional resistance of the screw exceeds the applied torque the spring 34 will yield and permit the clutch surfaces 26 and 32 to slip on each other, the incidental noise of said slipping warning the operator that the operation has been completed and that the tool should be withdrawn. The slipping of the clutch members 26 and 32 has the effect of applying tangential blows to the screw which further serves to tighten same to a greater degree.

When it is desired to use the device for removing screws, nuts and bolts the rotation of the driving spindle is reversed so that the torque is applied in a counter clockwise direction. If the screw or nut yields to the applied torque there is no slipping of the clutch members upon each other. However, if it does not yield and offers resistance to the rotation of the tool the clutch members will slip upon each other and in effect apply tangential blows to the screw or nut the application of such blows tending to effect a release of the screw or nut.

It will thus be seen that I have provided a tool which is adapted for driving or removing screws, nuts and bolts and which is automatically arrested in its operation when the torsional resistance exceeds the applied torque, the tendency to injure the tool or to deface the work thereby being completely eliminated.

It is to be understood that the form of my invention, herewith shown and described, is to be taken as a preferred example of the same, and that various changes in the shape, size and arrangement of parts may be resorted to, without departing from the spirit of my invention, or the scope of the appended claims.

I claim:

1. A device of the character described comprising a housing having a shank at one end thereof adapted for connection with a driving spindle, a toothed clutch member rigidly secured within the housing at the end adjacent the shank member, the other end of said housing comprising a wall with an opening therethrough, a complementary toothed clutch member mounted within the housing, said complementary clutch member being

independently rotatable and axially movable relative to the other clutch member, a spring within the housing for normally maintaining said clutch members in operative engagement, a longitudinally bored spindle mounted on said complementary clutch member and projecting through the wall opening of the housing, a tool shank mounted in said spindle for rotation therewith but being axially movable relative thereto, and a spring within the bore of the spindle abutting 10 against the tool shank for normally urging the tool shank outwardly of the housing.

2. A device of the character described comprising a housing, a shank member associated with said housing and adapted for connection with a driving spindle, a toothed clutch member rigidly secured at one end of the housing adjacent the driving spindle for rotation with the housing, a complementary toothed clutch member mounted in said housing, said complementary clutch member being independently rotatable and axially movable relative to the other clutch member, a depending spindle having a longitudinal bore and being associated with said complementary clutch member for movement therewith, a tool shank mounted in said spindle for rotation therewith but being axially movable relative thereto, resilient means mounted within the longitudinal bore for yieldingly holding said tool shank outwardly of said spindle, and spring 30 means for normally maintaining said clutch members in operative engagement, said clutch members arranged to be relatively movable when the torsional resistance on the depending spindle exceeds the applied torque of the driving spindle, the relative movement of said clutch members serving to apply tangential blows to said depending spindle.

3. A device of the character described comprising a housing formed of upper and lower sections, a shank mounted on the upper section adapted for connection with a driving spindle, a toothed clutch member rigidly secured within the housing at the end adjacent the shank member, the lower section of said housing having a wall at its lower end with an opening therethrough, a complementary toothed clutch member mounted within the housing, said complementary clutch member being independently rotatable and axially movable relative to the other clutch member, a spring within the housing abutting against the complementary clutch member and the lower wall of the lower section for normally maintaining said clutch members in operative engagement, said sections being movable relative to each other to vary the tension on said spring, a longitudinally bored spindle mounted on said complementary clutch member and projecting through the wall opening of the lower section, a tool shank mounted in said spindle for rotation therewith but being axially movable relative thereto, and a spring within the bore of the spindle abutting against the tool shank for normally urging the tool shank outwardly of the housing.

DAVID BRUZON.
